UNITED STATES PATENT OFFICE.

SAMUEL T. SKEEN, OF SANDOVAL, ILLINOIS.

MINER'S DRILL.

1,140,077.

Specification of Letters Patent. Patented May 18, 1915.

Application filed April 24, 1914. Serial No. 834,035.

To all whom it may concern:

Be it known that I, SAMUEL T. SKEEN, a citizen of the United States of America, a resident of Sandoval, in the county of Marion and State of Illinois, have invented certain new and useful Improvements in Miners' Drills, of which the following is a full, clear, and exact description, reference being had to the accompanying drawings, forming a part of this specification.

My invention relates to a drill, particularly adapted for use in drilling into coal deposits, the present invention being an improvement on the miner's drill shown in Patent No. 1,065,005, issued to me June 17, 1913.

One of the objects of the present invention is to produce a very strong drill structure adapted to withstand the severe stresses to which a miner's drill is subjected in drilling into sulfur and other hard material found in coal deposits.

The invention also includes certain very desirable details of construction which will be hereinafter described.

Figure I is a side elevation of a portion of a drill embodying the features of my invention. Fig. II is a side elevation partly in section showing the blades extended and locked in position. Fig. III is a longitudinal section taken approximately on line III—III, Fig. II. Fig. IV is a transverse section taken on the line IV—IV, Fig. I. Fig. V is a perspective view of one of the blades. Fig. VI is a perspective view of a thrust block adapted to engage the blades.

In the accompanying drawings: A designates a drill stem in the form of a spiral conveyer or worm having a thrust rod 1 at its inner end. The thrust rod is arranged within and slidably fitted to a blade holder B.

C designates blades pivotally connected to the blade holder by a pivot pin 2 screwed into the blade holder as seen in Fig. III.

3 designates a thrust block arranged between the thrust rod 1 and the blades C, said thrust block being arranged within and loosely fitted to the blade holder B.

50 The blade holder is provided with substantially T-shaped slots D for the reception of projections 4 carried by the thrust rod 1. These projections are preferably formed by a pin which extends through the thrust rod.

55 Before using my drill a small hole may be drilled into a coal deposit by a drill of any

suitable construction and my drill is then inserted into the hole with its pivoted blades in the position seen in Fig. I. The cutting edges of the blades are forced against the wall at the inner end of the small hole and the drill may be advanced and fed into the material by any suitable mechanism. During the first part of the drilling operation the blades are gradually extended, this action being due partly to the shape of the blades and partly to the pressure exerted on the blades by the transverse thrust block 3.

Fig. I shows the parts in the position they occupy at the beginning of the drilling operation and it will be noted that the projection 4 carried by the thrust rod 1 is so located in the slot D that the thrust rod is free to slide independently of the blade holder B. The thrust rod 1 engages the thrust block 3 and the latter engages the blades C. When the drill is advanced and rotated each projection 4 rides along a wall 5 of the slot D, this wall being parallel with the axis of the drill and the projection 4 being provided with the bearing face 6 which is also parallel with the axis of the drill. When the projections 4 pass over the ends of the straight walls 5 the thrust rod is turned independently of the blade holder and the projections 4 enter pockets 7 formed by the slot D. The parts then occupy the position seen in Fig. II and the projections 4 are interlocked with the blade holder to prevent the thrust members 1 and 3 from moving independently of the blade holder, and the blades are thus securely locked in their extended positions. It is important to note that the projections 4 ride along the straight walls 5 and that these projections cannot lock the blades until they are aligned with the pockets 7. At this time the blades are fully extended.

In the prior construction shown in Patent No. 1,065,005, the blade holder is provided with slots having inclined cam walls against which projections, corresponding to the projections 4, ride while the blades are moving to their extended positions. These cam walls co-operating with the projections tend to extend the blades at the beginning of the drilling operation, and I have found that this action places the projections under a very severe bending stress, the pins being very frequently bent in riding along such cam walls. The outward movement of the blades is resisted by the hard material in the coal de-

5 posits and if the blades are positively ex-
10 tended by means of a cam, some part of
the drill is necessarily strained in overcom-
ing the resistance offered by the hard ma-
terial. The projections 4 of my drill are not
15 subjected to a severe stress in traveling
along the straight walls 5 and to prevent a
cam-like action when the projections 4 enter
the pockets 7 these projections are provided
20 with straight faces which remain in contact
with the straight walls 5 until the blades
are fully extended.

When the drilling operation is completed
15 the drill is reversely rotated and gradually
withdrawn from the inner end of the hole.
At this time the projections 4 enter pockets
20 8 in the blade holder and the blades are
thus locked in their extended positions.
During this return movement of the drill
25 the cutting edges rotate in the same path
they followed in forming the hole, and any
irregularities or nicks in the cutting edges
of the blades will move freely over the cor-
30 responding projections formed in the hard
material by said blades during the drilling
operation. The object in locking the blades
in withdrawing the drill from the end of the
35 hole, is to positively hold the blades in posi-
tions where they will clear any projecting
portions of the hard material instead of
striking such material with the result of
40 bending the blades or injuring some other
part of the drill. After the blades are re-
leased from the material at the end of the
35 hole, the conveyer stem A is turned slightly
to release the projections 4 from the pockets
45 8, thereby unlocking the blades and permit-
ting them to swing toward each other. The
drill is then withdrawn from the hole. An-
other object in forming pockets 8 to receive
50 the projections 4 is to provide means for
locking the blades while they are being
sharpened. Each blade has a beveled cut-
ting edge 9 which may be filed while the
55 blades are secured to the blade holder. It
is of course quite important that the blades
be securely held in position during the sharp-
ening process and the pockets 8 are posi-
60 tioned to receive the projections 4 while the
beveled edges 9 are being filed. The pres-
sure of the file tends to turn the blades and
blade holder and the movement of the latter
65 is limited by the walls of the pockets 8
which engage the projections 4.

55 Each blade C is formed with a pair of
separated bearing faces 10 adapted to en-
gage the thrust block 3 and holder B at
points on opposite sides of the axis of the
70 drill. These widely separated bearing faces
60 are so located with respect to the axis of the
blades that the pivoted blades are very se-
curely held in the positions seen in Fig. II
when the thrust block is held against the
75 blades. To prevent material from collecting
65 between the bearing faces of the blades and

the thrust block where it would interfere
with the proper locking of the blades by the
projections 4, I form recesses 11 in the inner
faces of the blades. The end of the thrust
70 rod is provided with a recess 12 for the re-
ception of material lying between the thrust
block and the end of the thrust rod. To
prevent the blades C from swinging to their
extended positions while the drill is being
75 inserted into a hole, at least one of the blades
is preferably bent or offset as shown at 14,
to frictionally engage the blade holder,
thereby forcing both blades into frictional
engagement with the blade holder when the
80 parts occupy the positions shown in Fig. I.

I claim:

1. A miner's drill comprising a stem, a
thrust member at an end of said stem, a
blade holder slidably fitted to said thrust
member, blades pivoted to said blade holder
85 and adapted to be extended in response to a
movement of the drill, said blade holder be-
ing provided with a slot having a wall which
lies substantially parallel with the axis of
the blade holder and a pocket at the end of
90 said wall, and a projection carried by the
thrust member adapted to ride along said
wall when the blades are moving to their
extended positions and adapted to enter said
pocket to lock the blades in their extended
95 positions.

2. A miner's drill comprising a blade
holder, blades pivoted to said blade holder,
a thrust member slidably fitted to said blade
holder and adapted to turn independently of
the blade holder, the blade holder being pro-
100 vided with a slot having a wall which lies
substantially parallel with the axis of said
thrust member and also provided with a
pocket at an end of said wall, and a projec-
105 tion carried by the thrust member adapted
to ride along said wall when the thrust mem-
ber slides in said blade holder and adapted
to enter said pocket to lock the blades when
the thrust member turns independently of
110 said blade holder.

3. A miner's drill comprising a blade
holder, blades pivoted to said blade holder,
a thrust member slidably fitted to said blade
holder and adapted to turn independently of
the blade holder, the blade holder being pro-
115 vided with a slot having a wall which lies
substantially parallel with the axis of said
thrust member and also provided with a
pocket at an end of said wall, and a projec-
120 tion having a flat bearing face adapted to
ride along said wall when the thrust member
slides in said blade holder and adapted to
enter said pocket to lock the pivoted blades
125 when the projection reaches the end of said
wall.

4. A miner's drill comprising a stem, a
thrust member at an end of said stem, a
blade holder slidably fitted to said thrust
member, blades pivoted to said blade holder
130

- and adapted to be extended in response to a movement of the drill, said thrust member being movable independently of the blade holder while the blades are moving to their 5 extended positions, and a locking pin for locking said thrust member to secure the blades in their extended positions, said locking pin being carried by the thrust member, and the blade holder being provided with a 10 pair of pockets one of which is adapted to receive said locking pin during the operation of the drill, the other pocket being adapted to receive the locking pin when the blade holder is turned to sharpen the blades, 15 substantially as described.
5. A miner's drill comprising a stem, a thrust member at an end of said stem, a blade holder slidably fitted to said thrust member, blades pivoted to said blade holder 20 and adapted to be extended in response to a movement of the drill, said blade holder being provided with a substantially T shaped slot forming a pair of pockets and having a wall which lies substantially parallel to the axis of said thrust member, and a projection carried by said thrust member adapted to ride along said wall and adapted 25 to enter said pockets at the end of said wall, said projection serving as means for locking the blades in their extended positions when it lies within either of said pockets.
6. A miner's drill comprising a blade holder, blades pivoted to said blade holder, a transverse thrust block loosely fitted to 30 said blade holder and adapted to bear against said blades to hold the latter in extended positions, and a thrust rod slidably fitted to said blade holder and thrust block.
7. A miner's drill comprising a blade 35 holder, blades pivoted to said blade holder, a transverse thrust block loosely fitted to said blade holder and adapted to bear against said blades to hold the latter in extended positions, and a thrust rod slidably 40 fitted to said blade holder and thrust block, said thrust rod being provided with a recess for the reception of material lying between 45
- said thrust block and the end of the thrust rod.
8. A miner's drill comprising a blade 50 holder, blades pivoted to said blade holder, a thrust rod slidably fitted to the said blade holder, and a thrust block loosely mounted in said blade holder, said thrust block being arranged between the blades and the thrust 55 rod, and the blade being provided with bearing faces adapted to engage said thrust block.
9. A miner's drill provided with a blade 60 holder, blades pivoted to said blade holder, and a thrust member adapted to engage said blades to lock them in extended positions, the thrust member and blades being so formed that the points of contact between said parts are separated from each other 65 and located at opposite sides of the axis of the drill.
10. A miner's drill provided with a blade 70 holder, blades pivoted to said blade holder, and a thrust member adapted to lock said blades in extended positions, each of said blades being provided with separated bearing faces adapted to engage said thrust member.
11. A miner's drill comprising a stem, a 75 thrust member at an end of said stem, a blade holding member slidably fitted to said thrust member, blades pivoted to said blade holding member and adapted to be extended in response to a movement of the drill, one 80 of said members being provided with a slot having a wall which lies substantially parallel with the axis of the last mentioned member and a pocket at the end of said wall, and the other member having a projection adapted to ride along said wall when the blades are moving to their extended positions and adapted to enter said pocket to lock the 85 blades in their extended positions.

SAMUEL T. SKEEN.
